Primary Examiner — Darlington Ly*Assistant Examiner* — Giang Hoang Tran(74) *Attorney, Agent, or Firm* — JEEN IP LAW, LLC(57) **CLAIM**

The ornamental design for an electric bicycle, as shown and described.

DESCRIPTION

FIG. 1 is a top, front and left side perspective view an electric bicycle showing my new design;
FIG. 2 is a bottom, rear and right side elevation view thereof;
FIG. 3 is a left side elevation view thereof;
FIG. 4 is a right side elevation view thereof;
FIG. 5 is a rear elevation view thereof;
FIG. 6 is a front elevation view thereof;
FIG. 7 is a top plan view thereof;
FIG. 8 is a bottom plan view thereof;
FIG. 9 is an enlarged view of area "9" in FIG. 1;
FIG. 10 is an enlarged view of area "10" in FIG. 1;
FIG. 11 is an enlarged view of area "11" in FIG. 1;
FIG. 12 is an enlarged view of area "12" in FIG. 2;
